WILLIAM F. SEELEY, OF NEW HAVEN, CONNECTICUT, ASSIGNOR OF ONE-HALF TO
JOHN P. WILSON, OF NEW HAVEN, CONNECTICUT.

LOCK-CANAL MARINE TOY.

1,109,366.

Specification of Letters Patent.

Patented Sept. 1, 1914.

Application filed February 9, 1914. Serial No. 817,552.

To all whom it may concern:

Be it known that I, WILLIAM F. SEELEY, a citizen of the United States, residing at New Haven, in the county of New Haven 5 and State of Connecticut, have invented a new and useful Improvement in Lock-Canal Marine Toys; and I do hereby declare the following, when taken in connection with the accompanying drawings and the characters of reference marked thereon, to be a full, clear, and exact description of the same, and which said drawings constitute part of this application, and represent, in—

Figure 1 a plan view of a marine or hydrostatic, lock-canal toy constructed in accordance with my invention, showing both locks in operation and one boat in the higher level of the canal. Fig. 2 a view in vertical longitudinal section on the line 20 *a*—*b* of Fig. 1, showing the pump employed for replenishing the water in the higher level of the canal from the water-tank or reservoir. Fig. 3 a view of the toy in central transverse section on the line *c*—*d* of 25 Fig. 1, looking in the direction of the arrow *e*. Fig. 4 a corresponding view, looking in the direction of the arrow *f*. Fig. 5 a detached view in elevation of the lower level gates of one of the two locks. Fig. 6 30 a broken view in horizontal section on the line *h*—*i* of Fig. 4; showing the gates on the scale of Fig. 5.

My invention relates to an improved marine or hydrostatic lock-canal toy, the object being to produce an interesting and instructive toy clearly demonstrating the principle on which ships are raised and lowered by means of locks in a canal like the Panama Canal, now of such great interest to the public at large.

With these ends in view, my invention consists in a marine lock-canal toy having a continuous canal embodying upper and lower water levels and provided with an 45 outfit of locks so that miniature ships may be continuously operated through the canal without necessarily turning them about.

My invention further consists in a miniature lock-canal toy having certain details 50 of construction and combinations of parts as will be hereinafter described and pointed out in the claim.

In carrying out my invention as herein shown. I employ a shallow oblong water- 55 tank or reservoir 2 the size and form of

which may be varied as desired. Preferably this water-tank 2 will be made out of sheet metal but that is not material. Into this tank 2, I set a shallow tray 3 substantially conforming to it in size, having, as shown, rounded ends and also preferably made of sheet metal. The said tray 3 has an over-lapping flange 4 and is formed with a large central opening 5 rounded at one end, rectangular at the other end, and outlined by a vertical wall 6. The bottom of the said tray consists of an upper level 7 and a lower level 8, connected by a vertical wall 9 arranged transversely with respect to the length of the tray. As thus constructed the tray 3 contains a continuous channel consisting of two substantially U-shaped parts merging into each other on the line of the wall 9. One of these U-shaped parts forms what may be called the sea-level channel 10, and the other the upper level channel 11. The upper-level channel 11 is widened to form a miniature lake 12 which may be given the name of Gatun lake. Interposed between the two channels 10 and 11, I locate two corresponding locks 13 and 14. Each of these locks is furnished with a pair of short upper-level gates 15 and a pair of longer sea-level gates 16. These pairs of gates are sufficiently separated from each other to receive between them toy vessels such as 17, 18 and 19. Except for differences in length, the gates correspond in construction, each being furnished (Figs. 5 and 6) with a knuckle-bearing 20 working in vertical sockets 21 applied to the inner faces of the vertical channel-walls 6 and if preferred, the sockets 21 may be cast integral with the walls, depending upon the construction chosen for the tray 3. One gate of each pair of gates is provided with a wicket, so called, consisting of a rotary stem 22 furnished at its upper end with an operating-arm 23 and formed at its lower end with a vertical series of ports 24 registering with corresponding ports 25 formed in a reinforcement 26 located upon the lower inner corner of the gate, the other gate of the same pair being furnished with corresponding stop lugs 27. 20 The edges of the gates are also rabbeted as at 28 so as to be interlocked when closed, whereby they are made water-tight. When the locks are filled with water from the upper-level or lake channel 11 and then 105 110

opened, there will be an excess of water in the sea-level channel 10. To prevent an overflow, the sea-level channel 10 is provided with overflow ports 29 (Fig. 2) which permits the excess to flow into the water tank 2 from which it is pumped back into the upper-level or lake channel 12 by means of a small removable pump 30 of the bilge-pump type, or some other device answering the same purpose.

10 A miniature lock-canal toy, constructed as above described, provides a continuous channel of two levels equipped with two locks which permit the miniature ships 17, 18 and 19 to be raised and lowered just as the largest ships are handled in the Panama Canal or any other canal of the lock type.

15 Fig. 1 of the drawings, shows the vessel 17 in the lock 13 of which the upper-level gates 15 are closed and the sea-level gates 16 are open. The lock 13 may be designated as the Gatun lock. The vessel 18 is represented in the same figure as having passed through the Gatun lock 13 and into 20 Gatun lake 12 on its way to the Miraflores lock 14 the upper-level gates 15 of which are open, and the sea-level gates 16 of which are closed, and which contains the vessel 19. Supposing the vessel 17 to have just entered 25 the Gatun lock 13, as shown in Fig. 2, the sea-level gates 16 are then closed and the wicket in one of the upper-level gates 15 is opened, permitting the lock to gradually 30 be filled from the water in the upper-level channel 11. During the filling of the Gatun lock 13, the vessel 17 will slowly be raised to the level of the water in the upper-level channel 12. The wicket in one of the upper-level gates 15 will then be closed after which 35 the said upper gates will be opened to permit the vessel 17 to pass into the upper-level channel 11. The upper-level gates 15 are then closed and the wicket of the lower gates opened to permit the water in the lock 40 13 to flow into the sea-level channel 10, whereby the level of the water in the lock 13 will be reduced to the level of the water in the sea-level channel 10. As to the vessel 19 shown in Fig. 1, it may be supposed 45 to have just entered the Miraflores lock 14 previously filled to the level of the upper-level canal 11 by the closing of the lower-level gates 16 the wicket of which has, of

50 course, been closed. The upper gates 15 are now closed, their wicket 22 having been closed preparatory to the opening of the gates. The wicket 22 of the lower gates is now opened to permit the gradual subsidence of the water in the lock to the level of the sea-level channel 10 whereby the vessel 55 is allowed to descend to the level of the said lower channel, after which the lower gates 16 are opened to permit the vessel to proceed into the sea-level channel. This cycle is repeated for each vessel which may thus 60 be maneuvered continuously in the same direction through the two locks of the continuous canal.

55 As already stated, the form of the tank and tray may be changed and the details 70 of the lock gates altered. But in any form which my improved toy may assume, the canal will be continuous and the locks arranged so that each vessel may be deployed through the canal locks by constantly going 75 ahead, never turning about.

60 Although the principle of raising and lowering ships by means of locks is in itself simple, it is not generally understood even by adults. However, the whole operation 80 of a lock canal is perfectly and clearly demonstrated by my improved toy which will prove a source of interest, comment and instruction to children and "grown-ups."

65 I claim:—

70 In a lock-canal marine toy, the combination with a shallow water-tank or reservoir, of a tray adapted to be set into the said tank, having a flange overhanging the same and also having its bottom formed with an 75 upper and a lower level arranged to produce an endless channel comprising an upper level and a sea-level and inclosing a central space, two locks located in the said 80 endless channel and arranged therein for the continuous passage of miniature ships 85 through the channel in one direction without turning about; and overflow ports from the channel into the tank.

90 In testimony whereof, I have signed this 100 specification in the presence of two subscribing witnesses.

WILLIAM F. SEELYE.
